(57) **CLAIM**

I claim the ornamental design for an anchoring device, as shown and described.

DESCRIPTION

FIG. 1 is a top perspective view of an anchoring device showing my new design;

FIG. 2 is a top view of the embodiment of anchoring device shown in FIG. 1;

FIG. 3 is a side view of the anchoring device shown in FIG. 1;

FIG. 4 is a front view of the anchoring device shown in FIG. 1;

FIG. 5 is a bottom perspective view of the anchoring device shown in FIG. 1; and,

FIG. 6 is a bottom view of the anchoring device shown in FIG. 1.
